AWNNG

Dorothy M. Carpenter and Willis L. Wells, Clayton, Mo.; said Wells assignor to said Carpenter

Application August 4, 1949, Serial No. 108,543

4 Claims. (Cl. 160—172)

1

This invention relates to awnings, and more particularly to Venetian blind type awnings.

In general, the awning of this invention resembles a Venetian blind in comprising a series of slats or louvers which may be retracted and extended and which, when extended, may be pivoted to various angular positions ranging from a fully opened position to a fully closed position. It differs from the usual Venetian blind in that it is particularly adapted for use in generally horizontal or inclined position, as distinguished from use in vertical position, to serve as an overhead awning for outdoor areas, such as porch areas, thereby to provide shelter from the sun and rain when required. With the awning mounted generally horizontally or slightly inclined, gravity cannot be utilized to extend the slats, and an important feature of the invention is the provision of means for positively moving the slats from retracted to extended position so arranged as to permit the slats to be pivoted to various angular positions. Another important feature of the invention is the provision of special slats which, in closed position, interlock at their edges in such manner that the awning is rain-tight. Other features will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which several of various possible embodiments of the invention are illustrated:

Fig. 1 is a plan generally in section on line 1—1 of Fig. 2 of an awning embodying the invention, the slats of the awning being shown in extended and fully closed position, parts being broken away;

Fig. 2 is a vertical section taken on line 2—2 of Fig. 1, illustrating in dotted lines the slats in fully open position, parts being broken away;

Fig. 3 is a section taken on line 3—3 of Fig. 1, illustrating in dotted lines a slat in fully open position;

Fig. 4 is a fragment of Fig. 2 illustrating the slats in retracted position;

Fig. 5 is a schematic diagram of the slat extending and retracting mechanism;

Fig. 6 is a plan view of a second form of awning embodying the invention, parts being broken away and shown in section;

2

Fig. 7 is a transverse section taken on line 7—7 of Fig. 6;

Fig. 8 is a fragmentary longitudinal section taken on line 8—8 of Fig. 7, illustrating a closed position of the slats; and,

Fig. 9 is a view similar to Fig. 8 illustrating an open and retracted position of the slats.

Similar reference characters indicate corresponding parts throughout the several views of the drawings.

Referring to the drawings, Figs. 1—4 illustrate an awning 1 embodying the invention. As shown, the awning comprises an open rectangular frame 3 consisting of side frame members 5 and 7 and end frame members 9 and 11. The frame is illustrated in Fig. 2 in a sloping position such as it occupies when the awning is used as a roof. The side frame members 3 and 5 are identical. Each comprises a hollow beam 13, formed of sheet metal, for example, provided with a slot 15 in the wall of the beam toward the inside of the frame, the slot extending continuously from one end of the beam to the other. The slats of the awning are designated 17. The slots 15 in the beams 13 are somewhat wider than the slats 17. The beams 13, at their inside upper edges, are formed with a recess 19 to accommodate window sash or screens flush with the frame (see, for example, the dotted outline of a window 21 illustrated in Fig. 3). Within each beam 13 is a channel 23 fixed as by spot welding to the inside face of the outside wall of the beam 13 with its open side toward the slot 15 of the beam 13. The channels 23, which constitute side guides for the slats 17, are arranged centrally with respect to the slots 15.

Each slat 17 is provided with oppositely directed narrow flanges 25 and 27 at its longitudinal edges. The slats, as illustrated, are formed of sheet metal and the flanges formed by bending over their longitudinal edges. Each slat is provided centrally at its ends with pins 29 sized for an easy sliding fit in the side guide channels 23 of the side frame members 5 and 7. Each slat is also provided at each of its end edges with oppositely directed ears 31 and 33 located equal distances on opposite sides of the pin 29 at the respective end edge. These ears are formed by bending over integral portions of the slat to extend perpendicular to the plane of the slat. In each ear is fixed a cord fastener 34.

The slats 17 extend transversely of the frame 3 with their ends extending into the beams 13 through slots 15 and with their end pins 29 slidably and pivotally mounted in the side guide

channels 23 within the beams 13. Each slat is thus slidable longitudinally with respect to the frame and swingable about the axis of its pins 29 between a fully open position in a plane perpendicular to the plane of the frame (illustrated in dotted lines in Fig. 2) and a closed position substantially coplanar with the frame (illustrated in solid lines in Fig. 2). One end slat, the slat designated 17a, and as herein illustrated the slat which is located adjacent the end member 11 at the lower end of the sloping frame when the slats are extended, is provided with special end pins 29a having reduced-diameter ends 35 journaled in slides 31, the latter being slidable but non-rotary in the side guide channels 23. These slides are attached to the cable 39 of a cable system, generally designated 41, for extending and retracting the slats. This cable system is schematically illustrated in Fig. 5.

The cable 39 has reaches 43 within the side guide channels 23 extending from the slides 31 to pulleys 45 located at the ends of the channels at the head end of the frame 3 where the slats accumulate when retracted. The pulleys 45 are rotary on horizontal studs 47 fixed to the outside walls of the beams 13 of the respective side frame members 5 and 1. They are housed within the beams 13 and are located to guide the cable from reaches 43 into reaches 49 extending under the side guide channels 23 from the head end of the frame to pulleys 51 at the other end of the frame. Pulleys 51 are rotary on studs 53 extending perpendicular to the plane of the frame within the beams 13 outward of and below the ends of the side guide channels 23. Pulleys 55 are rotary on the studs 53 outward of and in line with the channels 23. Reaches 57 of the cable 39 extend within the side guides from the slides 31 to the pulleys 55 and reaches 59 extend transversely of the frame at its lower end from the pulley 55 on one side of the frame to the pulley 51 on the other. The arrangement is such that the cable may be moved in one direction (in the direction of the arrows in Fig. 5) to move the end slat 17a from the lower end of the frame toward the upper end, and in the opposite direction to move the slat 17a in the opposite direction.

The slats are linked together by control cords 61 and 63 on each side of the frame. Cords 61 extend the length of the frame within the beams 13 and are attached to the slats by means of the cord fasteners 34 in the ears 31. Cords 63 extend the length of the frame within the beams 13 and are attached to the slats by means of the cord fasteners 34 in the ears 33. The cords are fastened to the slats with the length of each segment of each cord extending from a cord fastener of one slat to the cord fastener of an adjacent slat somewhat less than the width of the slats. At the head end of the frame, the cords 61 and 63 are attached to the ends of control levers 65 fixed on a transverse shaft 67 journaled at its ends in the outside walls of the beams 13.

The arrangement is such that, when the end slat 17a is moved to extended position (Figs. 1 and 2), it acts through the cords 61 and 63 to pull the slats 17 to extended position wherein the pins 29 of the respective slats are spaced apart at intervals equal to the length of the segments of the cords between the cord fasteners. With the slats extended, they may be swung on the axes of their respective pins 29 by the cords 61 and 63. With the control levers 65 in the neutral position illustrated in dotted lines in Fig. 2, and with the

slats fully extended, the cords 61 and 63 are taut and the slats occupy their fully open position perpendicular to the plane of the frame 3. By rotating the shaft 67 to rock the levers clockwise from neutral position to the solid line position illustrated in Fig. 2, the slats may be swung clockwise toward their fully closed position substantially coplanar with the frame wherein the flange 25 of each slat is interlocked with the flange 21 of the adjacent slat in rain-tight fashion. The slats may be swung to any angular position intermediate their fully open and closed positions and retained in that position by retaining the levers 65 in appropriate angular position. By rotating the shaft to rock the levers counterclockwise, the slats may be swung counterclockwise.

As diagrammatically illustrated in Fig. 5, the cable 39 may be driven by taking one or more turns of the cable around an operating drum 69 at any convenient location, and driving the drum by an endless cable and pulley system 71. The mode of driving the cable 39 is not material. It may be driven in many ways other than that specifically mentioned. The shaft 65 may be turned by any suitable mechanism such as a cable-operated worm gear and worm drive as is conventional in Venetian blinds. The slats are releasably latched in extended position to keep the cords 61 and 63 taut by means of spring latches 73 fastened to the side guide channels 23 and having detents 75 extending through apertures 77 in the upper walls of the channels for engagement with the ends of the slides 31.

In the above-described awning 1, the slats can be swung about the axes of pins 29 only when the slats are in fully extended position or substantially so. In any other position of the slats, the cords 61 and 63 are loose, and operation of the control levers 65 is ineffective to swing the slats. Figs. 6-8 illustrate a somewhat different awning constructed to permit the slats to be swung to various angular positions in various positions of extension.

The awning 81 comprises an open rectangular frame 83 somewhat similar to the frame 3 of the awning 1 comprising side frame members 85 and 87, and head end and foot end members 89 and 91. The side frame members are identical, each comprising a hollow beam 93, formed of sheet metal, for example, having a slot 95 opening to the inside of the frame and extending from one end of the beam to the other. The beams are formed with flange portions 97 extending the length of the lower margin of the slots, and with recesses 99 at their inner upper edges to accommodate window sash or screens flush with the frame 83. Guide strips 101 are fixed within each beam providing guide slots 103 aligned with slots 95 and extending the length of the beams.

The slats of the awning 81 are designated 105. Each slat has a pair of pivot pins 107 located so that the slat may be pivotally mounted to swing about an axis substantially coincident with one longitudinal edge of the slat, and a flange 109 at its other longitudinal edge. As illustrated, each slat is formed of sheet metal. One longitudinal edge of the slat is bent around the pivot pins 107 to form a flange 111, with the pins extending endwise from the corners of the slat. The other longitudinal edge of the slat is bent over to form the flange 109. Flanges 109 and 111 are oppositely directed.

The slats 105 extend transversely across the frame with the pivot pins 107 extending into the beams 93 through the slots 95. The rounded flanges 111 of the slats are slidable and swingable

on the beam flange portions 97. Fixed on alternate pins 107 within the beams 93 are hubs 115 having flanges 117. Rotary on the hubs 115 are sprockets 119. Spring washers 121 react from the flanges 117 against the sprockets to provide friction slip drives so that when the sprockets rotate they frictionally drive the pins 107 to swing the slats. If, however, the slats are prevented from swinging, the sprockets will slip on the hubs. On the outer ends of the pins 107 are forks 123. These have annular grooves 125 receiving the edges of guide strips 101 defining the guide slots 103.

Housed in the hollow beams 89 are slat extending and retracting screws 127. These extend from one end of their respective beams to the other. As shown, each screw consists of a rod coiled into a long helix. It resembles a helical spring, but has no spring function. Throughout the greater length of a screw 127, the pitch of its convolutions or thread is somewhat less than the width of a slat, as indicated at 129 in Fig. 6. Adjacent the head end of the awning, where the slats are accumulated, the pitch of the convolutions or thread of the screws 127 is considerably reduced, as indicated at 131, for slat-accumulating purposes. The head and foot ends 133 and 135 of the screws 127 extend axially, and are journaled for rotation in the head and foot end members 89 and 91. The forks 123 on the ends of the pivot pins mesh with the screws 127, straddling the convolutions thereof. The arrangement is such that by rotating the screws 127 in one direction or the other, the forks 123 may be moved to retract or extend the slats. With close-pitch convolutions 131 at the head end of the awning, and with the sprockets 119 on alternate pins 107 on opposite sides of the awning, the slats may be closely accumulated at this end.

Also housed in the beams 93 are slat rotating screws 137. These also extend from one end of the respective beams to the other. Each screw 137 consists of a rod coiled into a long helix resembling a helical spring but having no spring function. The pitch of the convolutions or thread of the screws 137 is constant throughout their lengths. Sprockets 119 mesh with the screws 137. The arrangement is such that by rotating the screws 137 in one direction or the other, the slats may be frictionally driven and swung in one direction or the other. The head and foot ends 139 and 141 of the screws 137 extend axially, and are journaled in the head and foot end members 89 and 91.

Mechanism for driving the screws 127 and 137 to extend or retract the slats and to rotate them is generally designated 143. As shown, this mechanism includes a drive shaft 145 extending transversely across the frame 83 at its head end, journaled at its ends in the beams 93 as indicated at 147. Fixed on the head end 133 of one of the screws 127 (the screw in the side frame member 87 as illustrated) is a worm gear 149. This gear is in mesh with a worm 151 rotary on the shaft 145. The foot ends 135 of the screws 127 are coupled to rotate in unison by a chain and sprocket drive 155.

On the shaft 145 is a pulley 157 adapted to drive the worm 151 through a clutch 159 comprising a driving clutch element 161 on the pulley and a driven clutch element 163 on the worm. A cable 165 is provided to rotate the pulley 157. The pulley 157 is axially movable on the shaft and is biased in clutch-disengaging direction by a spring 167. It is provided with a cam element

169 cooperable with a cam element 171 fixed on the shaft. Cam element 171, as illustrated, is formed as a part of another pulley 173 pinned on the shaft 145. A cable 175 is provided to rotate the pulley 173 and the shaft. The head ends 139 of the screws 137 have bevel gears 177 fixed thereon. These are in mesh with bevel gears 179 fixed on the shaft 145.

To extend or retract the slats 105, the cable 165 is pulled to rotate the pulley 157 in appropriate direction. This causes the pulley to be cammed to the right as illustrated in Fig. 6 by the action of cam element 169 against cam element 171 to engage the clutch 159 and thereby to drive the worm 151. The pulley 173 and the shaft 145 resist rotation until the clutch is engaged. The worm 151 thereupon rotates the screws 127 to extend or retract the slats, according to the direction of rotation of the worm. As soon as the clutch 159 is engaged, the pulley 157 drives the shaft 145 through the cam elements 169 and 171. This drives the screws 137 through their bevel gear drives to rotate the sprockets 119 in such manner as to cause the slats to remain at whatever angular position they occupied at the start of the retracting or extending operation. It will be noted that as the slats are extended or retracted, they would be rotated due to the meshing of the sprockets 119 with the screws 137 except for this action of the screws 137 to retain the slats in their original angular position.

To swing the slats to different angular positions, the cord 175 is pulled to rotate the pulley 173 and the shaft 145 in appropriate direction. Under these circumstances, the clutch 159 remains disengaged, and the worm 151 is not driven so that the slats are not extended or retracted. Rotation of the shaft drives the screws 137 to rotate the sprockets 119 and swing the slats. In the closed position of the slats, the flanges 109 of one slat interlock with the flanges 111 of the adjacent slat in rain-tight fashion.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. An awning comprising side guides, slats having their ends slidably and pivotally mounted in the side guides, slat extending and retracting screws extending lengthwise of the side guides, means on the slats meshing with the screws whereby, upon rotation of the screws in one direction or the other, the slats may be retracted and accumulated at one end of the side guides or moved away from said end to extended positions, slat rotating screws extending lengthwise of the side guides, and means on the slats meshing with the slat rotating screws whereby, upon rotation of the slat rotating screws in one direction or the other, the slats may be swung to various angular positions about axes extending lengthwise of the slats.

2. An awning comprising side guides, slats having their ends slidably and pivotally mounted in the side guides, slat extending and retracting screws extending lengthwise of the side guides, means on the slats meshing with the screws whereby, upon rotation of the screws in one direction or the other, the slats may be retracted

and accumulated at one end of the side guides or moved away from said end to extended positions, slat rotating screws extending lengthwise of the side guides, and means on the slats meshing with the slat rotating screws whereby, upon rotation of the slat rotating screws in one direction or the other, the slats may be swung to various angular positions about axes extending lengthwise of the slats.

3. An awning comprising side guides, slats having pivot pins on their ends slidably and pivotally mounted in the side guides, slat extending and retracting screws extending the length of the side guides, forks on the ends of the pivot pins meshing with the slat extending and retracting screws, slat rotating screws extending lengthwise of the side guides, sprockets on the pivot pins meshing with the slat rotating screws, mechanism for driving the slat extending and retracting screws and the slat rotating screws in unison and for driving the slat rotating screws independently of the slat extending and retracting screws comprising a drive shaft geared to the slat rotating screws, a driving clutch element axially shiftable on the shaft, a driven clutch element rotary on the shaft geared to drive the slat extending and retracting screws, and cam means for shifting the driving clutch element into engagement with the driven clutch element when the driving clutch element is rotated relative to the shaft, said cam means thereupon acting to drive the shaft from the driving clutch element.

4. An awning comprising side guides, slats having pivot pins on their ends slidably and pivotally mounted in the side guides, slat extending and retracting screws extending the length of the side guides, forks on the ends of the pivot

pins meshing with the slat extending and retracting screws, slat rotating screws extending lengthwise of the side guides, sprockets on the pivot pins meshing with the slat rotating screws, mechanism for driving the slat extending and retracting screws and the slat rotating screws in unison and for driving the slat rotating screws independently of the slat extending and retracting screws comprising a drive shaft geared to the slat rotating screws, a driving clutch element axially shiftable on the shaft, a driven clutch element rotary on the shaft geared to drive the slat extending and retracting screws, and cam means for shifting the driving clutch element into engagement with the driven clutch element when the driving clutch element is rotated relative to the shaft, said cam means thereupon acting to drive the shaft from the driving clutch element, said sprockets being rotary on the pivot pins, and friction drive means between the sprockets and pivot pins.
